(57) **CLAIM**

The ornamental design for an electrical connector, as shown and described.

DESCRIPTION

FIG. 1 is a top, right side perspective view of an electrical connector, showing our new design;

FIG. 2 is a bottom, left side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side view thereof; and,

FIG. 8 is a left side view thereof.

The shadings in the figures show contour and not surface ornamentation.

The broken lines in the drawings are for the purpose of illustrating portions of the article that form no part of the claimed design.
